(57) **CLAIM**

The ornamental design for a zipper pull assist device, as shown and described.

DESCRIPTION

FIG. 1 is a perspective view of an exemplary embodiment of my new zipper pull assist device design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken line showing of chain in FIGS. 1-7 are for the purpose of illustrating environmental matter and forms no part of the claimed design.
